UNITED STATES PATENT OFFICE

SYLVESTER A. JOHNSON, OF NORTH PROVIDENCE, RHODE ISLAND, ASSIGNOR TO
SPEIDEL BROS., OF PROVIDENCE, RHODE ISLAND, A FIRM COMPOSED OF ALBERT
E. R. SPEIDEL AND EDWIN F. M. SPEIDEL, BOTH OF EDGEWOOD, RHODE ISLAND

WRIST-STRAP END MEMBER

Application filed May 15, 1929. Serial No. 363,360.

This invention relates to a watch strap end member commonly called an end hook for connecting the strap to the lug of a wrist watch, and has for its object to provide a simple and effective connection between the 5 watch strap and the end member so that end members of varying widths may be interchanged as desired to fit the lugs of different watches.

10 A further object of this invention is the provision of a tip on the end of a strap with an interchangeable connection between the tip and the end member for interchanging members of varying widths to fit different 15 wrist watch lugs as desired.

15 A still further object of this invention is the provision of a tongue and eye connection between the strap tip and the end member with the tongue so formed that it may be passed through the eye, and folded to form a 20 back wall of the portion with which it is integrally attached.

With these and other objects in view, the 25 invention consists of certain novel features of construction, as will be more fully described, and particularly pointed out in the appended 30 claims.

In the accompanying drawings:

Figure 1 is a top plan view of a portion of 35 a wrist watch strap provided with a tip and an end member, the latter being illustrated as connected to a watch which is partially shown in dotted lines.

Figure 2 is a sectional view taken on line 40 2-2 on Figure 1.

Figure 3 is a sectional view of the end member.

Figure 4 is a sectional view of the tip with the strap connected thereto and the tongue 45 in open position.

Figure 5 is a top view of a modified form of end member, and

Figure 6 is a modified view of a still different modified form of end member.

45 Wrist watches of different sizes and designs have lugs or bail members of varying widths thus necessitating the use of strap end members of varying or adjustable widths to properly fit the lugs of different wrist 50 watches, and in order to obviate the necessity

of carrying complete bracelets with varying sizes of end members I have provided a means by which the end members alone may be easily interchanged so that the retail jeweler may fit the correct end member to the customer's watch and then easily attach this end member to the wrist band by the simple bending of a tongue into position by manual manipulation or with the assistance of a pair of pliers and the following is a detailed description of the present embodiment of this invention illustrating the preferred means by which these advantageous results may be accomplished.

With reference to the drawings, 10 designates the dotted line showing of a portion of a wrist watch having a bail or lug 11 to which the end member 12 is attached. The end member may be of any of the desired forms to be secured to a watch casing; that which I have illustrated has a body 13, with an extended shank 14 formed into a hook 15, with a tongue 16 pivotally mounted at 17 between the side walls 18 of the body of the end member. The tongue is provided with the finger piece 19 to lift tongue for detaching purposes, while suitable spring means are provided to hold the tongue in the position illustrated in Fig. 2.

An eye 20 is formed on the end member 80 through which there extends the tongue 21 of the tip 22, the tip being attached permanently to the strap 23 by means of a suitable clamp consisting of strap engaging pieces 24 and arms 25 folded thereover to force the 85 same into engagement therewith.

The tip 22 is reduced as at 26 and the end member 12 is likewise reduced as at 27 so that these reduced parts at their junctures will be of equal width, regardless of the width of 90 the strap or shank portion 14 of the end members for the varying assortment of wrist watch lugs which will be carried by the jeweler. The reduced portion 27 is always 95 of a width to cooperate with an equal width of the reduced portion 26 of the tip and conform to the arc of a circle 28 on either side thereof, and enhance the appearance of the device.

The tongue 21 extends from the reduced 100

portion 26 and the eye 20 is also formed on this portion which portions are of a standard size and will always properly cooperate one with the other. The tongue 21 after being passed through the eye 20 is folded between the side walls 29 of the tip which is of a width substantially the space between these side walls and forms a bottom wall in its position 30 in Figure 2 so that a neat appearance of the assembly is provided.

10 The end member which I have illustrated in Figure 1 has its shank end square across but in certain cases, where the shape of the watch may be different, I may concave this end as at 31 in Figure 5 or convex it as at 32 in Figure 6 to cooperate with the wrist watch to which it may be attached.

I claim:

1. In combination with a wrist watch strap, a tip, means for squeezing portions of the tip against opposite faces of the strap to clamp the same on the end of the strap, said tip having a bendable tongue extending therefrom, and an end member adapted to be secured to the lug of a wrist watch having watch bail engaging means at one end and an eye at the other end, said tongue being inserted through said eye and bent rearwardly contiguous to the tip to detachably secure said tip and end member together.
2. In combination with a wrist watch strap, a tip, means for squeezing portions of the tip against opposite faces of the strap to clamp the same on the end of the strap, said tip having a reduced extremity, and a bendable tongue extending therefrom, an end member adapted to be secured to the lug of a wrist watch having watch bail engaging means at one end and a reduced portion at the other end of the size of the reduced extremity of said tip with an eye therein, said tongue being inserted through said eye and bent rearwardly contiguous to the tip to detachably secure said tip and end member together.
3. In combination with a wrist watch strap, a tip, means for squeezing portions of the tip against opposite faces of the strap to clamp the same on the end of the strap, said tip having side walls and a bendable tongue extending therefrom of a width substantially equal to the distance between said side walls, an end member adapted to be secured to the lug of a wrist watch having an eye to receive said tongue, said tongue being bendable through said eye and rearwardly between said walls to substantially close the space therebetween and to form a portion of a back wall for said tip, said tip and end member having their contiguous portions of similar width and formed to simulate an integral device.

In testimony whereof I affix my signature.
SYLVESTER A. JOHNSON.
